UNITED STATES PATENT OFFICE

2,268,907

PREFABRICATED BUILDING STRUCTURE

Charles H. Scott, Cincinnati, Ohio, assignor to
The Globe-Wernicke Company, Norwood, Ohio,
a corporation of Ohio

Application April 10, 1939, Serial No. 266,945

7 Claims. (Cl. 189—34)

This invention relates to building structures and particularly to structures of the type in which the various units are prefabricated along standardized lines so that the work of erecting a building may be performed by relatively unskilled labor and in a very short time.

It is an object of my invention to provide a structure as outlined above which will involve a number of standardized parts of simple design and which will be inexpensive to manufacture. It is another object of my invention to provide such a structure in which the various elements are fastened together in a simple manner, and in which the fastening means insures registry of the parts and in which the fastening means are concealed from view, whereby the structure from either the inside or the outside presents a smooth finish. A further object of my invention involves the provision of an arrangement whereby if it should become desirable to move the building to a different location substantially the entire structure can be salvaged and rebuilt elsewhere. It is a still further object of my invention to provide a structure which may be thoroughly insulated and which while both inside and outside walls may be made from steel, will not cause a high heat loss through the walls because there is no metal to metal contact between the inside and outside walls.

These and other objects of my invention which will be described in more detail hereinafter or which will be apparent to one skilled in the art upon reading these specifications, I accomplish by that certain construction and arrangement of parts of which I have shown a number of exemplary embodiments.

Reference is now made to the drawings forming a part hereof, and in which:

Figure 1 is a front elevation of an exemplary building made according to my invention, with parts broken away to show the wall structure.

Fig. 2 is a roof view of the structure of Fig. 1, with parts of the roof material broken away to show the roof deck. Fig. 3 is a cross sectional view taken on the line 3—3 of Fig. 1, showing progressively from left to right the assembly of the structure.

Fig. 4 is a view similar to Fig. 3 showing a reversed structure.

Fig. 5 is a perspective view of a portion of a wall panel.

Fig. 6 is a detail perspective view of one of the fastening keys.

Fig. 7 is a partial perspective view of the man-

ner in which the locking key fastens two adjacent wall panels together.

Fig. 8 is a partial cross sectional view on the line 8—8 of Fig. 1, showing the foundation and the bottom of a wall.

Fig. 9 is a cross sectional view taken on the line 9—9 of Fig. 1, showing the upper end of a wall and the roof deck.

Fig. 10 is a cross sectional view taken on the line 10—10 of Fig. 9.

Fig. 11 is a horizontal cross sectional view through an inside wall or partition.

Fig. 12 is a cross sectional view taken on the line 12—12 of Fig. 1, showing the door jam construction.

Fig. 13 is a cross sectional view taken on the line 13—13 of Fig. 1, and showing the window sill construction.

Fig. 14 is a cross sectional view taken on the line 14—14 of Fig. 1, showing an upper portion of the window.

Fig. 15 is a cross sectional view taken on the line 15—15 of Fig. 1, showing the side construction of the window.

Fig. 16 is a perspective view with parts broken away showing an exemplary porcelain enamel panel which may be used for the outside wall.

Fig. 17 is a partial perspective view of a panel having means for engagement with a wooden nailing strip.

Fig. 18 is a fragmentary horizontal cross sectional view through one of the nailing strips 20 of Fig. 11 showing how the panels of Fig. 17 are applied.

For the purposes of this disclosure I have shown my invention in connection with a small building such as may be suitable for gasoline stations and the like. It will be understood, of course, that a building according to my invention may be made 40 of much greater size and may be modified as to shape and floor plan in any desired way.

Briefly, in the practice of my invention, I provide a number of wall panels such as are shown in Fig. 5, the edges being formed so as to embrace 45 a wooden nailing strip. Adjacent panels are fastened together by means of a key shown in Fig. 6, and an outer surface may be nailed to the wooden nailing strips. It will be understood, of course, that the wall structure may be reversed 50 so that the nailing strips may face inwardly whereby any desirable material such as Masonite or any of the well known wall boards may be nailed directly to the nailing strips or if desired, a lath may be nailed to the strips and the interior wall may be plastered in the usual manner.

Preferably, I provide a concrete foundation indicated at 10 in Fig. 8, which will, of course, be of a size and form specified by the architect. Preferably bolts 11 are imbedded in the concrete and the concrete will be extended to form the floor 12 of the building. Angle irons 13 are fastened to the foundation by means of the bolts 11 provided with appropriate nuts. The wall members 14 may stand on the angle irons 13.

As shown in Fig. 5, the wall members comprise a panel portion 15, the edges of which are joined normal to the plane of the panel 15, as at 16, and the edges of the portion 16 are formed in a channel shape as indicated generally at 17. Slots 18 are provided in the portion 16, said slots 18 having enlarged central portions as shown. Adjacent panels are fastened together by means of a key 19 of H-shape, shown in Fig. 6. The slots 18 are of a size to admit one of the upper right hand portions of the H and the central enlarged portion of the slots 18 is of a size to permit the key to be turned to a horizontal position. The key is then positioned to the bottom of the slots 18, as shown in Fig. 7. The slots 18 are accurately spaced in the web 16 so that the operation of driving the key 19 down to its seat in its slot 18 brings about a registry of the panels 15.

By reference to Figs. 3 and 4 it will be noted that the assembly of a number of panels 14 bring adjacent channel portions 17 together to form a hollow rectangular member partially open at the opposite side from the panels 15. Within these hollow rectangular members are seated the nailing strips 20. It will be noted that the strips have an extending ridge indicated at 20a which projects beyond the channel portion 17 so that if a metal member is nailed to the nailing strips there will be no contact between it and the panels 14. By reference to Fig. 4 it will be seen that the construction may be reversed and that an insulating portion or wall board of any desired type indicated at 21, may be nailed to the nailing strips 20.

A preferred construction for the outer wall in the form of Fig. 3 is shown in more detail in Figs. 8, 9 and 16. This construction involves a number of panels or pans shown in perspective in Fig. 16. These pans 22 are in the form of a small shallow box having extending flanges at one end at 22a. The flanges are preferably drilled as at 22b and the pans are provided with studs 23 and slots 24. These pans are applied from the bottom upwardly, each pan being nailed in position through the perforations 22b and a succeeding pan being placed in position with the slots 24 embracing the studs 23, the succeeding panel again being nailed as before. The lowermost panel is slightly different in form, as shown in Fig. 8, in that instead of the flange with the slots 24, it is provided with a hook portion 25 engageable with a hooked element 26 which is screwed to the structure as at 26a. Preferably small spaces will be left between the pans 22 and these may be filled with a calking compound. If desired, some sort of insulating material may be applied under the pans 22, as indicated at 26. This may be some form of insulating board or it may be a material similar to tinfoil. Preferably, the pans 22 will be given a coat of porcelain enamel in desired color so that the exterior surface of the building may very easily be washed. It will be understood that at the corners of the building the structural elements may be given a curved form as shown at 27 in Figs. 3 and 4.

Interior walls may be built if desired in the same manner as exterior walls or the structure may be simplified as shown in Fig. 11. Here the panels 14 may be the same as those described above and are fastened together in the same manner, and are also fastened to the outer walls in the same manner as described heretofore. In this case, however, use may be made of panels 28 which may be simply of channel shape and the nailing strips 20 may be slotted to accept the arms of the channel shaped panels 28. These may be screwed or nailed to the strips 20 as indicated at 29. According to a preferred arrangement, however, the panels 28 are formed with inwardly struck up elements 28a in the flanges thereof, as shown in Fig. 17. The elements 28a on the opposed flanges are preferably staggered in relation to each other. In assembling these panels, the flanges of a pair of adjacent panels 28 are forced into the slot in a strip 20 at a point about an inch above their desired position. The panels are then pounded downwardly in their plane. During this latter movement, the elements 28a cut themselves into the body of the strip 20 as shown in Fig. 18, and will not pull out. The parts can of course be salvaged if a building is to be moved, by tearing the panels out, or sliding them back in the way they were inserted. In rebuilding, the panels are inverted, and thus by virtue of the staggering of the elements 28a, they will enter portions of the strip 20 which have not been cut up. It will of course be clear that under some conditions, the inside wall construction may be satisfactory for an outside wall, and I therefore do not desire to limit myself as to the location of a wall by virtue of its construction.

The roof deck construction will now be described. Near the tops of the side walls I provide angle irons 30 which may be fastened as by self threading screws 31 to the side walls. If desired, finished strips 32 may be applied so as to give the interior of the building a smoother appearance. The roof deck preferably consists of a number of beams 33 which may be in cross section similar to the panels 14 above described. Preferably, however, they will be narrower so as to be better capable of sustaining load. These are similarly laid across the building on the angles 30 and any desired building board may be nailed to the nailing strips 20 which are the same as heretofore described, as indicated at 34. Wooden finishing strips of triangular cross section indicated at 35 are provided and preferably a three-ply mopped on roofing is applied as shown at 36. The roofing material is preferably extended up over the side walls as indicated at 37, and an angle member 38 is provided to hold the roofing in place. The second angle 39 is also fastened as by means of a self threading screw 40 passing through the angles 39 and 37 through the roofing and into the side walls, as may be clearly seen in Figs. 9 and 10. The angle 39 is provided as a means of attachment for a cornice member indicated generally at 41. This may, of course, be of any desired configuration and the lower flange thereof at 42 is provided with slots just the same as the slots 24, so that it may engage with the studs 23 at the uppermost of the pans 22. The inner end of the cornice 41 may simply be fastened to the angle 39 as by means of a nut and bolt generally indicated at 43.

The window and door construction is extremely simple and may be modified in a number of ways. The door jam construction is shown in Fig. 12, 75 and it consists of a jam member generally indi-

cated at 44, of any desired shape providing a portion to cooperate with the closed door as indicated at 45. The member 44 may be fastened in place by means of self threading screws 46, or in any other desired manner. A fragment of the door is indicated at 47. It will be clear from this figure that the door may be made to open inwardly or outwardly as desired.

The window frame structure is very similar to the door frame structure and it is contemplated that any conventional steel window may be utilized whether of the sash or casement type. The side frames take the form of a member 48 which is quite similar to the member 44 just described, and it is fastened in place in the same manner. The window frame is fastened in place by means of self threading screws or similar devices 49, preferably in such manner that the putty 50 used in the glazing operation covers the screw head as shown. For the lower and upper sills I prefer to provide angle members 51 which may be fastened to the wall members as by means of the self threading fastening member 52. The sill members may be of any desired shape, although I prefer to make the upper member of the shape indicated at 53 so as to project slightly from the front wall of the building and the lower sill is preferably of the form indicated at 54 having a portion 55 to overlap the outer wall to insure against seepage of water.

It is to be understood that the description given above is exemplary in its nature and that the structure may be modified in numerous respects which will suggest themselves to one skilled in the art. It is to be understood, therefore, that I do not intend to limit myself otherwise than as pointed out in the claims which follow.

Having now fully described my invention, what I claim as new and desire to secure by Letters Patent, is:

1. A building wall structure comprising a number of panels of generally channel shape having spaced hook-like portions and having means for fastening a number of panels together between the planes thereof and said hook shaped portions, said hook shaped portions when in assembled relationship forming substantially tubular elements having longitudinal openings, insulating members disposed in said tubular portions and extending through said openings and being slotted in said extensions, and another number of panels of simple channel shape affixed to said insulating portions with the arms of said channels entering said slots.

2. In combination with a plurality of building wall panels of generally channel shape, means for releasably fastening adjacent panels together, comprising slots in the arms of said panels, said slots having enlarged central portions and said slots being accurately spaced from the planes of said panels, and a plurality of H-shaped fastening keys, the cross portion of said H being of a width to form a drive fit in the end portions of said slots, whereby said keys may be inserted into the slots, rotated through an angle of substantially 90 degrees, and driven down into the ends of the slots to fasten two panels together, and coincidentally to register the planes thereof.

3. In combination with a plurality of building wall panels of generally channel shape, means for releasably fastening adjacent panels together, comprising slots in the arms of said panels, said slots having enlarged central portions and said slots being accurately spaced from the planes of

said panels, and a plurality of H-shaped fastening keys, the cross portion of said H being of a width to form a drive fit in the end portions of said slots, whereby said keys may be inserted into the slots, rotated through an angle of substantially 90 degrees, and driven down into the ends of the slots to fasten two panels together, and coincidentally to register the planes thereof, the length of said cross member being substantially equal to twice the gauge of the panels whereby the panels are also drawn tightly together.

4. A building wall structure comprising a number of panels of generally channel shape having hook portions along their edges spaced from the plane of said panels, means between the plane of said panels and said hook portions for fastening said panels together, said hook portions in assembled relation providing substantially tubular portions having openings longitudinally thereof, insulating members seated in said tubular portions and extending through said openings and other panels comprising shallow channel shaped members having engaging elements inwardly struck out from the flanges thereof, said insulating members being slotted, and contiguous flanges of adjacent of said other panels entering said slots and held therein by means of said engaging elements.

5. A building wall structure comprising a number of panels of generally channel shape having hook portions along their edges spaced from the plane of said panels, means between the plane of said panels and said hook portions for fastening said panels together, said hook portions in assembled relation providing substantially tubular portions having openings longitudinally thereof, insulating members seated in said tubular portions and extending through said openings and other panels comprising shallow channel shaped members having engaging elements inwardly struck out from the flanges thereof and constituting an abrupt shoulder facing the web, said insulating members being slotted, and contiguous flanges of adjacent of said other panels entering said slots and held therein by means of said engaging elements.

6. A building wall structure comprising a number of panels of generally channel shape having hook portions along their edges spaced from the plane of said panels, means between the plane of said panels and said hook portions for fastening said panels together, said hook portions in assembled relation providing substantially tubular portions having openings longitudinally thereof, insulating members seated in said tubular portions and extending through said openings and other panels comprising shallow channel shaped members having engaging elements inwardly struck out from the flanges thereof and constituting an abrupt shoulder facing the web, said engaging elements in opposed flanges being staggered in relation to each other, said insulating members being slotted, and contiguous flanges of adjacent of said other panels entering said slots and held therein by means of said engaging elements.

7. A building structure comprising a plurality of substantially standard outer panels and a number of substantially standard inner panels, one of said number of panels in assembled relationship constituting also a number of studs for said structure, means for releasably fastening adjacent panels together comprising slots in the arms of said panels, said slots having enlarged central portions and said slots being accurately spaced from the planes of

spaced from the planes of said panels, and a plurality of H-shaped fastening keys, the cross portion of said H being of a width to form a drive fit in the end portions of said slots, whereby said keys may be inserted into the slots, rotated through an angle of substantially 90 degrees, and driven down into the ends of the slots to fasten two panels together, and coincidentally to reg-

ister the planes thereof, a number of substantially insulating strips held in assembled relationship to said studs and means for fastening said other number of panels to said insulating strips, whereby direct conduction of heat from the inner to the outer panels or vice versa, is eliminated.

CHARLES H. SCOTT.
